UNITED STATES PATENT OFFICE

CHARLES D. ROBARTS, OF CISCO, TEXAS

AUTOMATIC STANDING-VALVE TAP

Application filed October 30, 1928. Serial No. 316,098.

The present invention relates to improvements for removing standing valves from the working barrels of oil wells, and has for its principal object to provide a device that will 5 expeditiously and efficiently remove a standing valve or drop valve from the working barrel of an oil well whenever the occasion arises.

One of the important objects of the present 10 invention is to provide an automatic standing valve tap which includes a rotatable stem having a tap formed on its lower end, for engagement with the standing valve that is to be removed, said stem being arranged for 15 rotation within a barrel that has means carried by the upper end thereof for connection to a set of jars for lowering the device into the well, means being arranged within the barrel for cooperation with the stem to normally hold the same against rotation, additional means being provided for automatically effecting the rotation of the stem and the tap carried thereby when the locking 20 means is released.

25 A further object is to provide a valve tap of the above mentioned character wherein the parts are so constructed as to enable the same to be readily and easily assembled or disassembled, the device being further at all 30 times efficient and reliable in operation.

Still a further object is to provide a device of the above mentioned character which is simple in construction, inexpensive, strong and durable, and further well adapted to the 35 purpose for which it is designed.

Other objects of the invention will become apparent as the nature of the invention proceeds and when taken in connection with the accompanying drawings.

40 In the accompanying drawings:

Figure 1 is a side elevation of the automatic standing valve tap embodying my invention.

Figure 2 is a longitudinal sectional view 45 through the barrel, the cap at the upper end thereof and the head secured on the lower end of the barrel, showing the means for locking the stem against rotation.

Figure 3 is a detail perspective view of the 50 stem per se.

Figure 4 is an enlarged detail for more clearly showing the locking means for the stem.

Figure 5 is a sectional view, taken approximately on the line 5—5 of Figure 4, looking 55 upwardly, and

Figure 6 is a detail perspective view of the coil spring for association with the rotatable stem.

In the drawings, wherein for the purpose 60 of illustration is shown the preferred embodiment of my invention, the numeral 1 designates a cylindrical barrel that is internally threaded at its upper and lower ends. A cap 3 is formed with a slightly reduced externally threaded portion 4 on the bottom thereof for threaded engagement within the upper end of the barrel 2. A somewhat greater reduced threaded neck 5 is formed 65 on the top of the cap for connection with the 70 adjacent end of the suspension means (not shown) that is used to lower and raise the device into the well. As is clearly shown in Figure 2, the cap is formed with a socket 6 that extends upwardly from the bottom to a 75 point below the neck portion 5 and the upper end of the socket is tapered as at 7.

A head 8 is externally threaded, at its 80 upper end, for threaded engagement within the lower open end of the barrel 2 and this head is formed with a socket 9, in the upper portion thereof, said head being further formed with a bore 10 that affords communication between the bottom of the socket and the bottom of said head. The head is further 85 provided with a cavity 11, that extends downwardly from the bottom of the socket 9 to a point adjacent the bottom of the head, and extending through the bottom of this cavity is a plunger rod 12, on the upper end of which 90 is carried the latch 13 that is adapted to project into the bottom of the socket for a purpose to be presently described.

An expansible coil spring 14 is arranged 95 within the cavity 11 and encircles the plunger rod 12, in the manner as clearly shown in Figures 2 and 4. A cotter pin 15 extends through a transverse opening formed in the lower end of the plunger rod 12 for engage- 100

ment in the bottom face of the head 8 to prevent displacement of the plunger rod.

Forming a salient part of the present invention is the elongated stem 15. This stem is formed at its lower extremity with the threaded standing valve engaging tap 17, the same being tapered. A reduced pin 18 extends from the upper end of the stem and the upper end of the pin is tapered. This 10 pin is adapted for vertical movement within the recess 6 formed in the cap 3.

An annular shoulder 19 is formed on the intermediate portion of the stem 16 for disposition within the socket 9 and the bottom 15 face of this shoulder is formed with the equidistantly spaced recesses 20 for cooperation with the spring pressed latch 13 to prevent rotation of the stem 16. The portion of the stem directly above the shoulder 19 is slightly 20 tapered as clearly illustrated in the drawings. Furthermore, this shoulder 19 is formed with an opening 21 for receiving the lower end of a coil spring 22, that forms an important part of the present invention. 25 This coil spring encircles the upper portion of the stem 16 within the barrel 2 and the upper end of the coil spring is disposed laterally for disposition in an opening provided therefor in the side of a barrel. In this manner, the ends of the coil spring are secured to the barrel and shoulder of the stem respectively.

In use, the stem 16 is initially forced upwardly in the barrel, so as to permit the 30 winding of the coil spring around the stem, and it is of course understood that the latch 13 is retracted from the recessed bottom face of the shoulder, in order to permit the free movement of the stem in one direction. After 35 the spring has been properly wound, when the spring latch is released, said latch will automatically engage in one of the recesses 20 and secure the stem against further rotation of its own accord. The tool is then 40 ready for use, and when lowered into the well and the tap 17 is engaged with the standing valve, by pushing downwardly on the set of jaws to which the tool is connected, the latch 13 may be disengaged from the 45 recessed shoulder, whereupon the spring will automatically turn the stem 16 and cause the tap 17 to be rigidly associated with the standing valve to provide a connection between the 50 standing valve and the stem, whereupon this standing valve may be removed from the well by pulling upwardly on the suspension 55 means to which the threaded neck 5 is attached.

60 It will thus be seen from the foregoing description that I have provided an automatic standing valve tap which will at all times be efficient and reliable in its operation, and furthermore due to its simplicity, the parts 65 can be constructed at a very low cost and also

assembled or disassembled without any difficulty.

While I have shown the preferred embodiment of my invention, it is to be understood that various changes in the size, shape and arrangement of parts may be resorted to, 70 without departing from the spirit of the invention or the scope of the appended claims.

I claim:

1. In a device of the class described, a barrel, a longitudinally movable stem extending through the bottom of said barrel, a standing valve engaging and supporting tap formed on the lower end of the stem, a coil spring encircling the stem for disposition within the barrel, one end of the spring being secured to said stem, the other end being secured to the barrel, said spring being placed under tension when the stem is turned in one direction, and releasable means carried by the barrel for cooperation with the stem to hold the spring under tension and prevent rotation of the said stem, said releasable means including a latch carried by the bottom of the barrel, a shoulder formed on the stem for disposition above the latch, the bottom of the shoulder being formed with a recess to receive the latch. 75

2. In a device for removing standing valves, a barrel open at its respective ends, a cap secured on the upper end of the barrel for attachment to a suspension means, a head detachably secured on the lower end of the barrel and provided with a socket in the top thereof, an elongated stem extending through the head and its socket, the upper end of the stem extending into the barrel, a standing valve engaging and attaching tap formed on the lower end of the stem, a normally expanded coil spring within the barrel encircling said stem, one end of the coil spring being secured to the barrel, the other end to said stem, and cooperating means between the head and the stem for securing the stem against rotation and to maintain the coil spring under tension, said coil spring effecting the rotation of the stem when the locking means is released, said locking means comprising a spring pressed latch extending upwardly through the head into the socket, a head formed on the stem for disposition within the socket, said shoulder being provided with recesses in the bottom face thereof for cooperation with the latch. 90

In testimony whereof I affix my signature. 100
CHARLES D. ROBARTS.
